SHIRT COLLAR

Chauncey C. Chapel, Peabody, Kans.

Application September 9, 1937, Serial No. 163,143

1 Claim. (Cl. 2—127)

It is a well known fact that collars, whether attached to a shirt or separably connected therewith, often shrink to such an extent that they cannot be closed properly at the front, an unsightly and untidy appearance resulting, and it being necessary to cast aside a shirt or collar which otherwise is capable of further service.

The foregoing being understood, this invention aims to provide a construction wherein the aforementioned undesirable conditions will be obviated, an adjustment of the collar at the front, being possible, through the instrumentality of a tongue which is so housed at its free end that it will not impede the adjustment of a necktie about the collar.

The device is of use not only in connection with shirts which have shrunk, but also for the purpose of enabling the wearer to have a perfectly fitting shirt or collar, between the ordinary half-inch measurements. Moreover, it will produce a better fitting shirt or collar even though the article, in the absence of the device forming the subject matter of this application, may conform roughly and generally to the size required.

Another object of the invention is to secure a perfectly fitting collar, even though the ordinary collar button is retained.

It is within the province of the disclosure to improve generally and to enhance the utility of devices of that type to which the present invention appertains.

With the above and other objects in view, which will appear as the description progresses, the invention resides in the combination and arrangement of parts, and in the details of construction hereinafter described and claimed, it being understood that a shirt maker or collar maker can depart from the precise embodiment of the invention herein disclosed, within the scope of what is claimed, without departing in corresponding degree from the spirit of the invention.

In the drawing:

Fig. 1 shows in elevation, a shirt equipped with the device forming the subject matter of this application;

Fig. 2 is a section on the line 2—2 of Fig. 1;

Fig. 3 is a section on the line 3—3 of Fig. 1;

Fig. 4 is a perspective showing the parts separated;

Fig. 5 is a perspective showing a separable collar embodying the invention, the shirt being disclosed beneath it.

In Figs. 1 to 4, the numeral 1 marks a collar, including an outer wall 4, and an inner wall 2, the inner wall 2 being connected to a shirt 3. The inner wall 2 embodies a first or outer layer 5, and a second or inner layer 6, the said layers being stitched together, after the common practice. Between the layers 5 and 6 of the inner wall 2

there exists a pocket 7, access to which is had through a slit or opening 8, formed in the outer layer 5 and set back a little from the end edge of the inner wall 2, as Fig. 1 will disclose. The inner wall 2 has a projecting tongue 9, the free end of which is adapted to be inserted into the pocket 7, through the opening 8. The free end of the tongue 9 can slide in the pocket 7 and the collar may be adjusted as to size, the tongue 9, however, bridging the space between the forward 10 edges of the inner wall 2 and no unsightly appearance will result, an observation which will be manifest when Fig. 1 of the drawing is noted. Because the end of the tongue 9 is housed in the pocket 7, the end of the tongue in nowise will interfere with the adjustment of a necktie about the collar.

In Fig. 5, parts hereinbefore described have been designated by numerals already used, with the suffix a. Here the collar 1a is separable from 20 the shirt 3a. The inner wall 2a has a tongue 10 overlapped by the tongue 9a. The collar band of the shirt is marked by the numeral 11 and has the usual button holes 12. The tongue 10 has a button hole 14, and there is a button hole 15 25 in the tongue 9, the button hole 15 being enlarged and elongated sufficiently so that it can slide freely on the collar button (not shown) without interfering with the sliding movement of the tongue 9a in the pocket, through the opening 8a. 30

The device is simple in construction but it provides for an adjustment in the absence of which many collars, whether attached to a shirt or not, otherwise would become useless. The untidy effect produced by a gaping collar will be obviated. The tongue 9, fitting closely but slidably in the opening 8, will keep the forward ends of the collar in line and one end of the collar will not move upwardly above the other end, with correspondingly undesirable results as to appearance.

Having thus described the invention, what is claimed is:

A collar comprising a wall embodying inner and outer layers defining a pocket therebetween, 45 the outer layer having an opening giving access to the pocket, the wall being provided with transversely projecting over-lapped tongues bridging the space between the ends of the wall, one tongue having a free end longitudinally slidable 50 in the pocket and insertible thereinto through the opening, the tongues having button holes, and the button hole of said one tongue being enlarged and elongated to afford free longitudinal sliding movement of said one tongue on a collar button 55 and corresponding to the sliding movement of said one tongue in the opening and in the pocket.
